UNITED STATES PATENT OFFICE.

FREDERICK J. HARDMAN, OF DAYTON, OHIO, ASSIGNOR TO GENERAL MOTORS CORPORATION, A CORPORATION OF DELAWARE.

ENGINE-STARTING APPARATUS.

Application filed July 24, 1924. Serial No. 728,034.

This invention relates to starting apparatus for internal combustion engines and comprises an electric motor for driving a gear which is movable into and out of engagement with a gear driven by the engine, such as the fly wheel gear. The driving connection between the engine and motor are such that, when the engine becomes self-operative, the motor gear will be automatically thrown out of engagement with the engine gear.

It is among the objects of the invention to provide a manually operable device for shifting the motor gear into engagement with the engine gear and for causing the motor to operate the motor gear to crank the engine, the manually operable means to include devices for permitting the motor gear to be demeshed automatically from the engine gear, although the manually operable device may be maintained in the position which produced the engagement of the motor gear with the engine gear. In carrying out this object of the invention, there is provided a pedal connected with a lever which shifts the motor gear toward the engine gear. The mechanism connecting the pedal and lever is constructed so that, when the engine becomes self-operative, the motor gear may be automatically demeshed and the leverage of the connections between the pedal and shifting lever be automatically modified, with the result that, instead of urging the motor gear toward the engine gear, continued pressure upon the pedal will tend to have the opposite effect, after the engine has become self-operative.

A further object of the invention is to provide for disconnecting the motor from the current source in case the engine should fail to start and the motor gear should be retained in mesh with the engine gear.

Further objects and advantages of the present invention will be apparent from the following description, reference being made to the accompanying drawing.

Fig. 1 is a fragmentary view, partially in section, showing the engine starting apparatus in normal position, the motor being disconnected from the engine gear.

Fig. 2 is an end view of the apparatus showing Fig. 1, partially in section, the section being taken on the line 2-2 of Fig. 1.

Fig. 3 is a view similar to Fig. 1, but showing the apparatus in position for cranking the engine.

Fig. 4 is a view similar to Fig. 3, showing the apparatus in position after engine has become self-operative and automatically demeshed the motor gear, the pedal being maintained in engine starting condition.

Referring to the drawings, an electric motor 20, including a field frame 21 and an end frame 22, operates an armature shaft 23, supported by frame 22 and provided with spiral splines 24 which terminate adjacent collar 25, attached by pin 26 to shaft 23. The motor gear 27 which is adapted to engage the engine fly wheel gear 28 is rotatable upon and axially movable along the shaft 23, the motor gear 27 being provided with internal spiral splines or threads which co-operate with the splines 24 of shaft 23.

The end frame 22 is provided with brackets 30 which support the shaft 31 upon which is loosely mounted a lever hub 32 connected with forked lever arms 33 and 34. The arms of fork 33 each carry a roller 35 for engaging a groove 36 located between the flanges 37 of a sleeve 38 which is integral with or attached to the gear 27. A spring 39 attached by stud 40 to one of the brackets 30 and attached by stud 41 to the forked lever 33 tends to maintain the lever 33 in the position shown in Fig. 1.

The apparatus for operating the forked lever 33, comprises a pedal 42, located within convenient reach of the driver of an automobile. Pedal 42 is attached to a rod 43 which projects through a cup member 44 attached to the floor board 45, the lower end of the rod 43 being connected at 46 with a lever 47. A spring 48 located between the pedal 42 and the cup member 44 normally maintains the lever 47 in the position shown in Fig. 1.

Lever 47 is attached by pin 49 to the shaft 31 which is in turn attached by pin 50 to a lever 51. Levers 47 and 51 support the ends of a rod 52 which provide a pivotal support for the trip lever arms 53 and 54 which are connected together by a pin 55 retained by cotter pins 56. Pin 55 also provides a pivotal support for the head 57 of a trip rod 58 which extends through an apertured block 59 provided with trunnions 60

which pivotally support the block 59 between the branches of the forked lever 34. A spring 61 is located between the head 57 of rod 58 and the pivoted block 59.

5 The trip lever 53 is provided with an extension 62 adapted to be engaged by either of the studs 63 or 64 which project from one of the brackets 30 as shown in Fig. 2.

The switch for connecting the motor with 10 a source of current comprises a case 70 enclosing insulated contacts 71 and 72 attached to terminal bolts 73 and 74, respectively. These contacts are adapted to be bridged by a conducting tube 75 mounted 15 upon an insulated sleeve 76 of moulded material in which is imbedded a switch rod 77 attached to the lever 47. The tube 75 and sleeve 76 are received by an aperture 20 non-conducting collar 78 supported by the switch case 70.

The operation of the invention is as follows:

To start the engine, the pedal 42 is depressed to cause the lever 47 to move from 25 the position shown in Fig. 1, to the position shown in Fig. 2. During this operation of the pedal 42, motion is transmitted from lever 47 to the motor gear 27, through the following elements: rod 52, trip lever arms 30 53 and 54, pin 55, rod head 57, spring 61, trunnions 60, forked lever 33, forked lever 34, rollers 35, flange 37, sleeve 38, which in turn is connected with gear 27.

During this downward movement of the 35 pedal 42, the switch contacts 71 and 72 are connected by the tube 75. In case the motor gear enters the engine gear without butting, the motor switch will be closed after partial engagement of the gear has been effected.

40 Operation of the motor will cause the gear 27 to be moved axially until it engages the stop collar 25. Then the motor will turn the gear 27 and thereby turn the engine gear 28 to crank the engine. If, after the 45 pedal 42 is depressed to move the gear 27 into gear 28, the teeth of gear 27 fail to register with the tooth spaces of gear 28, thereby preventing further movement to the right of gear 27, continued movement of 50 the pedal 42 downwardly will compress the spring 61 and close the motor switch. The motor, being energized, will rotate the shaft 23 to bring the motor gear 27 into registration with the spaces of gear 28, whereupon 55 the compressed spring 61 will be released to move the gear 27 quickly into engagement with the gear 28. The rotation of the motor will cause the gear 27 to be screwed against the stop collar 25 and thereafter to 60 be rotated to crank the engine as described.

When the engine becomes self-operative, due to the superior rotation of the engine gear 28 and the spiral spline connection between the gear 27 and the shaft 23, the gear 65 27 will be thrown out of mesh with the en-

gine gear automatically, regardless of whether the pedal 42 has been released. In case the pedal 42 is maintained in downward position to hold the lever 47 in the position shown in Fig. 4, the lever 33 is permitted 70 to rotate clockwise after the gear 27 is automatically demeshed.

By comparing Figs. 3 and 4, it will be noted that in Fig. 3 the spring 61 tends to act upon the lever 33 to move it in a counter-clockwise direction but in Fig. 4, the leverage of the spring 61 has been modified so that it now tends to move the lever 33 in a clockwise direction and to assist in demeshing the motor gear 27. This condition 80 of affairs is brought about in the following manner:

After the lever 47 is moved from the position shown in Fig. 1, to that shown in Fig. 2, the trip lever arms 53 and 54 rotate relative to the lever 47, as well as being rotated about the shaft 31. This rotation is brought about by the engagement of studs 63 with the extension 62 of trip lever arm 53. This relative movement between levers 47 and 53 90 causes the leverage of the action of spring 61 upon the lever 33 to be decreased. Therefore, after the pedal 42 moves the gear 27 into engagement with the gear 28, the leverage of pedal 42 with respect to the lever 32 is materially weakened. Consequently, when the end thrust upon the motor gear 27 is reversed by the superior rotation of the engine gear, this force tending 95 to move the pinion 27 toward the left (in the drawings) is sufficient to shift the rod 58 from the position shown in Fig. 3 to the position shown in Fig. 4.

The rod 58 and the lever 34 may be regarded as the arms of a toggle joint. These toggle arms are drawn more nearly into alignment as the apparatus is moved from the position shown in Fig. 1 to that shown in Fig. 2. Consequently, when the engine suddenly becomes self-operative, the sudden thrust of the gear 27 toward the left will cause the toggle pivot 60 to move from a position to the left of a center line joining the pin 55 and shaft 31, to the right of this center line. The spring 61, when thus located as shown in Fig. 4, assists in holding the gear 27 out of engagement with the gear 28. 110

115 The starter is restored to normal condition by release of the pedal 42 which causes the lever 47 to return to its original position, thereby producing rotation of the trip lever 53, relative to the shaft 31. By virtue of the engagement between the stud 64 and the extension 62 of the lever 53, rotation of levers 53 and 54, relative to the lever 47, 120 will take place. This movement rotates the pin 55 relative to the shaft 31 and produces counter-clockwise rotation of the rod 58 and spring 61 relative to the trunnion 60.

125 In case the engine should fail to start, 130

after the gear 27 has been meshed with the gear 28, the pedal 42 may be released to open the motor switch, although the lever 33 will remain in the position which has produced

5 the meshing of the gears. The lever 47 is permitted to return to normal position indicated by the dot and dash line position 47^a in Fig. 3.

I claim:

- 10 1. Engine starting apparatus comprising, in combination, a gear connected with an engine to be started; an electric motor; driving connections between the gear and motor including a pinion and means whereby the pinion will be automatically demeshed from the engine gear; a motor switch; and manually controlled means for shifting the pinion into engagement with the gear and for closing the switch, said means including a pedal, a spring motion transmitting device between the pedal and pinion and normally located so that pedal operation will cause the pinion to be yieldingly engaged with the engine gear, and provisions whereby the demeshing motion of the pinion will cause the spring to be located so as to permit the pinion to remain out of mesh with the engine gear regardless of continued pressure upon the pedal.
- 15 2. Engine starting apparatus comprising; in combination, a gear connected with an engine to be started; an electric motor; driving connections between the gear and motor including a pinion and means whereby the pinion will be automatically demeshed from the engine gear; a motor switch; and manually controlled means for shifting the pinion into engagement with the gear and for closing the switch, said means including a pedal, a
- 20 spring motion transmission device between the pedal and pinion and normally located so that pedal operation will cause the pinion to be yieldingly engaged with the engine gear, and provisions whereby the de-
- 25 meshing motion of the pinion will cause the spring to be located so as to permit the pinion to remain out of mesh with the engine gear regardless of continued pressure upon the pedal.
- 30 3. Engine starting apparatus comprising; in combination, a gear connected with an engine to be started; an electric motor; driving connections between the gear and motor including a pinion and means whereby the pinion will be automatically demeshed from the engine gear; a motor switch; and manually controlled means for shifting the pinion into engagement with the gear and for closing the switch, said means including a pedal, a
- 35 spring motion transmission device between the pedal and pinion and normally located so that pedal operation will cause the pinion to be yieldingly engaged with the engine gear, and provisions whereby the demeshing motion of the pinion will cause the spring to be located so as to tend to hold the pinion out of mesh with the engine gear if pressure upon the pedal is continued after the engine starts.
- 40 4. Engine starting apparatus comprising, in combination, a gear connected with an engine to be started; an electric motor; driving connections between the gear and motor including a pinion and means whereby the pinion will be automatically demeshed from the engine gear; a motor switch; and manually controlled means for shifting the pinion into engagement with the gear and for closing the switch, said means including a pedal, a
- 45 spring motion transmission device between the pedal and pinion and normally located so that pedal operation will cause the pinion to be yieldingly engaged with the engine gear, and provisions whereby the de-
- 50 motion of the pinion will cause the spring to be located so as to tend to hold the pinion out of mesh with the engine gear if pressure upon the pedal is continued after the engine starts.
- 55 5. Engine starting apparatus comprising, in combination, a gear connected with an engine to be started; an electric motor; driving connections between the gear and motor including a pinion and means whereby the pinion will be automatically demeshed from the engine gear; a motor switch; and manually controlled means for shifting the pinion into engagement with the gear and for closing the switch, said means including a pedal, a
- 60 pinion shifting lever, a spring transmitting motion from the pedal to the lever normally in a direction for causing the pinion to be shifted toward the engine gear when the pedal is pressed, and provisions whereby the demeshing motion of the pinion will cause

the spring to transmit from the pedal, while pressed, pressure in a direction tending to hold the pinion out of mesh with the engine gear.

4. Engine starting apparatus comprising, 70 in combination, a gear connected with an engine to be started; an electric motor; driving connections between the gear and motor including a pinion and means whereby the pinion will be automatically demeshed from the engine gear; a motor switch; and manually controlled means for shifting the pinion into engagement with the gear and for closing the switch, said means including a pedal, a pinion shifting lever, means for connecting the pedal and lever and normally disposed to transmit from the pedal, when pressed, motion tending to move the lever into position for meshing gears, and provisions for reversing the effect of the connecting means 75 automatically in response to the demeshing motion of the pinion, whereby continued pressure upon the pedal after the engine starts will tend to maintain the pinion in demeshed position. 90

5. Engine starting apparatus comprising, 95 in combination, an engine gear; an electric motor; driving connections between the gear and the motor including a pinion and means whereby the pinion will be automatically demeshed from the engine gear; a motor switch; manually-controlled means for shifting the pinion into engagement with the engine gear and for closing the switch, said means including a pedal and motion-transmitting means between the pedal and the pinion, comprising a toggle having its members normally angularly disposed so that pressure upon the pedal causes the pinion to be shifted into engine gear enmeshment, 100 the toggle being so constructed and arranged that its members will be located by the demeshment of the pinion from the gear in such a manner as to transmit motion from the pedal in a reverse direction to the pinion-shifting device before the pedal is released, a spring for restoring the pedal, and means responsive to the movement of the pedal to normal position for restoring the toggle members to normal position. 110 115

6. Engine starting apparatus comprising, in combination, an engine gear; an electric motor; driving connections between the gear and the motor including a pinion and means whereby the pinion will be automatically 120 demeshed from the engine gear; a motor switch; manually-controlled means for shifting the pinion into engagement with the engine gear and for closing the switch, said means including a pedal-operated lever, a forked lever connected with the pinion and pivoted coaxially with the pedal-operated lever, an arm extending from the forked lever, a trip lever pivoted on the pedal-operated lever intermediate its ends, and a 125 130

- yieldable member interposed between the forked lever and the free end of the trip lever and cooperating with said forked lever to form a toggle-like structure which normally operates to move the pinion into engine gear engagement when the pedal is operated, and which will trip to another position to permit demeshment of the pinion and engine gear by engine operation while the pedal is maintained in operated position, and means co-operating with the trip lever to restore the toggle device to normal position in response to movement of the pedal to normal position.
- 15 7. Engine starting apparatus comprising, in combination, an engine gear; an electric motor; driving connections between the gear and motor, including a pinion and means whereby the pinion will be automatically demeshed from the engine gear; a motor switch; manually-controlled means for shifting the pinion into engagement with the engine gear and for closing the switch, said means including a pedal, a pinion-shifting lever, a trip lever pivotally carried by the pedal and including an extension adapted to engage stops to shift said trip lever into proper positions when the pedal is operated, and a toggle connecting the pedal and pinion-shifting lever, said toggle having its members normally angularly disposed to cause the pinion to be moved into gear enmeshment when the pedal is depressed, the angular position of said toggle members being changed so as to cause the pressure of the pedal to move the pinion in the opposite direction when the engine, upon self operation, has shifted the pinion out of gear enmeshment and before the pedal is released, the trip lever extension engaging one of its stops to shift the said lever into its normal position when said pedal is released, whereby the toggle members are again restored to their normal relative positions.
